US0D1086778S

(12) **United States Design Patent** (10) **Patent No.:** **US D1,086,778 S**
(45) **Date of Patent:** **** Aug. 5, 2025**

(54) **COFFEE MACHINE**

- (71) Applicant: **SharkNinja Operating LLC**, Needham, MA (US)
- (72) Inventors: **Andrew Reynolds**, Providence, RI (US); **Dan Kestenbaum**, Brookline, MA (US)
- (73) Assignee: **SharkNinja Operating LLC**, Needham, MA (US)
- (**) Term: **15 Years**
- (21) Appl. No.: **29/969,678**
- (22) Filed: **Oct. 23, 2024**

Related U.S. Application Data

- (63) Continuation of application No. 29/874,000, filed on Apr. 12, 2023, now Pat. No. Des. 1,048,792.
- (51) **LOC (15) Cl.** **07-01**
- (52) **U.S. Cl.** **D7/309**

(57)

CLAIM

The ornamental design for a coffee machine, as shown and described.

DESCRIPTION

FIG. 1 is a front perspective view of the coffee machine; FIG. 2 is another front perspective view thereof; FIG. 3 is a bottom perspective view thereof; FIG. 4 is a front view thereof; FIG. 5 is a rear view thereof; FIG. 6 is a left side view thereof; FIG. 7 is a right side view thereof; FIG. 8 is a top view thereof; and, FIG. 9 is a bottom view thereof.

The broken lines shown in the figures show features of the coffee machine that form no part of the claimed design.

1 Claim, 9 Drawing Sheets
